UNITED STATES PATENT OFFICE

2,603,897

SIGN

Glenn G. Wagoner, Inglewood, Calif.

Application October 10, 1947, Serial No. 779,126

1 Claim. (Cl. 40—30)

1

This invention relates to signs.

The invention has for an object the provision of a sign made up of a series of transparent envelopes depending one from the other and adapted to enclose elongated cards having characters on both sides thereof, the envelopes being reversible as to position so that first one side of the cards is presented to view and then the other side.

A further object is to provide a structure carrying sign elements, which sign elements are readily changed with a minimum of effort and time.

A further object is to provide a reversible type sign which is so constructed as to be durable and inexpensive in cost of manufacture, and generally superior to signs of the reversible type now known to the inventor.

A further object is to provide a sign having a transparent envelope, which envelope is secured between end caps in a novel manner.

A further object is the provision of a sign which is attractive in appearance and may be used as a counter display sequentially advertising different commodities.

With the above mentioned and other objects in view, the invention consists in the novel and useful provision, formation, construction, association, and relative arrangement of parts, members and features, all as shown in certain embodiments in the accompanying drawing, described generally, and more particularly pointed out in the claim.

In the drawing:

Figure 1 is a fragmentary, partially sectional view of a sign and its framing embodying the invention.

Figure 2 is an enlarged longitudinal sectional view of one of the sign elements of the invention.

Figure 3 is a fragmentary transverse sectional view on the line 3—3 of Figure 1.

Figure 4 is a sectional view on the line 4—4 of Figure 1.

Figure 5 is an enlarged detail of certain elements of the invention taken on the line 5—5 of Figure 1.

Figure 6 is a fragmentary enlarged sectional view looking in the direction of the arrow 6 of Figure 1, and

Figure 7 is a fragmentary perspective view of a modified form of sign element.

Referring now with particularity to the drawing, I have shown in Figure 1 a cabinet 1 adapted to house a plurality of sign elements 2. The sign elements are of the type which may be relatively turned to the end that the appearance

of the sign is changed for the onlooker. The sign elements are identical in construction, although the means for connecting certain ones thereof to the cabinet may vary. Referring first to Figure 2, a sign element includes a tubular transparent envelope 3 which may assume any transverse section desired, whether it be oval in form as shown in Figure 7, or cylindrical as shown in Figure 3. Caps 4 and 5 are provided for the ends of each envelope. The caps conform to envelope section, that is to say, if the envelope shown at 3 is circular, the cap rim would be correspondingly circular. Each cap includes an end wall 6 and a rim 7, which rim is provided with an annular inwardly facing bead 8. Ends of the envelope are fitted within the cap rims and abut against the beads 8, as shown at 9. This construction is followed for all of the sign elements.

Each sign element 2 is interconnected with other sign elements in such a manner that a turning of one sign element will produce a simultaneous turning movement in the other sign elements. This is accomplished by providing a series of interconnecting cords for the sign elements. The caps at the ends of the transparent envelopes are all interconnected in the same manner, and therefore the cord connection between the caps 5 for the different sign elements will be described. Cord 10 is connected to cap 5 at 11, and is passed around said cap and downwardly to where it interconnects cap 5 of sign element 2, shown at 12, at the point 13. Cord 14 connects with cap 5 of the uppermost sign element at 15. Cord 14 is then connected to the sign element 2, shown at 12, at 16. The next lower sign element 2, shown at 17, is interconnected with the sign element shown at 12 by cords 18 and 19, cord 18 being secured to the sign element shown at 12, at 20, and to the sign element shown at 17, at 21, while cord 19 is connected to sign element shown at 12, at 22, and with the sign element shown at 17, at 23. This procedure is followed for the descending sign elements.

The uppermost sign element is adapted to be rocked or oscillated, and to accomplish this, the caps 4 and 5 are both provided with axially aligned trunnions 24 and 25. These trunnions are adapted to fit within bearing portions of the side walls 26 and 27 of the cabinet. For instance, in Figure 6, one side wall is provided with an entrance slot 28, which leads to the bearing portion 29 for one of the trunnions. It is intended that the upper and lowermost sign elements

should both be provided with trunnions, and that said trunnions should be received within bearing portions provided therefor, as illustrated in Figures 1 and 6. The intermediate sign elements do not carry trunnions. In this manner, the sign elements maintain a given relationship and do not swing out of alignment as the sign elements are oscillated. To assure that the sign elements maintain a given alignment, I provide end guides 30, 31, 32, and 33, for the uppermost and lowermost sign elements, which guides lie adjacent the caps carried by said sign elements. These guides are secured to the cabinet framing.

One of the trunnions of the uppermost sign element carries a pinion 34. This pinion is engaged by the teeth of rack 35, the rack teeth being held in engagement with the pinion by a keeper 36. One end of the rack is pinned at 37 to a disc 38, the disc in turn being mounted on a shaft 39, leading to a gear reduction unit 40. The gear reduction unit, in turn, is driven by a small electric motor 41. The gear reduction unit, motor, and associated elements are all mounted on the top wall 42 of the cabinet. When the motor is energized, the gear reduction unit is driven in the usual manner which, in turn, rotates shaft 39 at a reduced speed to turn disc 38 and cause reciprocation of the rack 35. Reciprocation of the rack produces rotary oscillation of the uppermost sign element, which through the cord connections with the depending sign elements produces like rotary oscillation thereof.

Each transparent envelope is adapted to have diametrically positioned therein a sign element 43. The sign elements may take the form of elongated cards, upon which notations of some character may appear on both surfaces thereof. The sign elements may either be held frictionally within the envelopes or may be positively held therein by means of channel guides 44 and 45 diametrically positioned within the envelope. Such guides may be formed of transparent material, which is secured to the transparent envelope in any manner, such as by a plastic glue, or by heat. In order to place the cards in position, one end cap is removed from each sign element and a card inserted within the envelope followed by replacing the end cap.

That form of the invention shown in Figure 7 does not differ in essential detail from the form shown in the other figures, save and except that the sign elements are oval in cross section. When this construction is followed, guides such as depicted at 44 and 45, need not be used as the inserted cards will maintain their position therein. In place of cords, I may use straps of small width, such as shown at 46 for interconnecting the end caps.

The cabinet 1 may take any configuration desired, such as outlined by the front wall 47, the cabinet being mounted upon a suitable base 48. There may be a rear door 49 to permit access within the cabinet. The cabinet is intended to have illuminating means so that the sign elements are rendered visible at night. In the form of the invention depicted in Figure 1, the device may carry a plug 50 to be received in any outlet box connected with a source of electric supply. The small type of the device may be placed in various locations, such as in a lobby, or on a counter, and when the motor is energized, the device will operate without further attention.

The operation, uses and advantages of the invention are as follows:

The transparent envelope of each sign element may be ornamented on the surface thereof so as to form what may be termed a framing for any card placed therein. In Figure 1, the transparent envelope has such a framing, as shown at 51. There is a similar framing for the transparent envelope for that form of the invention shown in Figure 7. Such a framing may be imprinted upon the envelope or painted thereon. The elongated cards for placement within the envelopes bear imprinting of some form on both surfaces. This is illustrated for one surface of each card in Figure 1. When the motor is energized, the sign elements are oscillated simultaneously first in one direction and then the other. The sign elements are maintained in alignment due to the connection between the framing and the uppermost and lowermost sign elements by providing detachable caps for the transparent envelopes. Access within the envelopes is each of accomplishment. The caps give rigidity to the envelopes and preferably the caps are formed of metal.

When a sign of the character of this invention is used for outdoor advertising purposes, the notations on the cards for insertion within the transparent envelopes may be light reflector type buttons, with the result that as light strikes the buttons, the characters thereon will glow and produce quite a dazzling effect, particularly as the sign elements are oscillated to produce different signs.

It is within the purview of the invention to change the geometric form of the transparent envelopes, which may be triangular in place of circular or ovoid, and when triangular, it is evident that the oscillation of each triangular element would be in steps of 60 degrees. In this manner, three different signs would be presented to view.

I claim:

In sign construction, a cabinet, a plurality of transparent envelopes adapted to be suspended one below the other, end caps for said envelopes, each end cap formed with an internal bead adapted to limit cap engagement with an envelope, each envelope adapted to transversely carry therein an elongated card bearing indicia on both surfaces thereof, cords interconnecting the end caps in such a manner that reversal of movement of the uppermost envelope produces like reversal of movement of all other envelopes, the end caps of the uppermost and the lowermost of said envelopes provided with trunnions journaled in said cabinet, and means for producing oscillatory rotation of one of said trunnions.

GLENN G. WAGONER.
